METHOD OF MAKING NECKTIES

Valentine Naftali, Mount Vernon, N. Y.

Application May 5, 1943, Serial No. 485,689

2 Claims. (Cl. 2-146)

1

This invention relates to neckties. More particularly, my invention is concerned with an improved method of making neckties of the type disclosed in my Patent No. 2,174,993, dated October 3, 1939, for Method of making neckties.

One of the objects of my invention is to provide a novel method of making four-in-hand neckties which shall represent an improvement in the method of stitching neckties disclosed and claimed in my said Patent No. 2,174,993, and by means of which the distortion due to stretching which usually occurs when making the necktie up into a knot, will be minimized.

Another object of my invention is to provide a novel and improved method of making four-in-hand neckties which shall be characterized by the simplicity of the steps involved and which at the same time shall produce a necktie of greatly enhanced appearance.

Still another object of my invention is to provide a novel and improved method of making four-in-hand neckties by machine sewing which shall have the appearance of being handmade.

Other objects of my invention will in part be obvious and in part hereinafter pointed out.

In the accompanying drawing, in which is shown one of the various possible embodiments of my invention,

Fig. 1 is an elevational view of a cut-to-pattern necktie fabric folded longitudinally with the wrong side outermost and stitched in accordance with my invention;

Figs. 2 and 3 are enlarged cross-sectional views taken substantially along the lines 2-2 and 3-3, respectively, of Fig. 1;

Fig. 4 is an elevational view of the necktie shown in Fig. 1 after it has been turned inside out and as viewed from the back of the necktie;

Fig. 5 is an elevational view of a longitudinal edge thereof;

Fig. 6 is an enlarged cross-sectional view taken substantially on the line 6-6 of Fig. 4;

Fig. 7 is an elevational view similar to Fig. 1, but illustrating a modified form of my invention; and

Fig. 8 is an enlarged cross-sectional view taken substantially along the line 8-8 of Fig. 7.

My invention is concerned with neckties of the four-in-hand type which are manufactured by the so-called reversal process or in other words, by those processes wherein the necktie fabric is first folded as desired with the wrong side outermost, then stitched and afterward turned inside out and pressed.

Referring now in detail to the drawing, I have 55 throughout its length and therefore many times

2

shown in Figs. 1 to 6 thereof, a necktie of the class herein under consideration and made in accordance with my invention.

In Fig. 1, I have illustrated a necktie fabric 10 of customary design and style which has been cut to a predetermined pattern so as to produce what is termed a self-lined necktie. The fabric 10 is folded longitudinally substantially in half, with the wrong side of the material outermost, to provide two adjacent layers 10a and 10b, connected by a folded longitudinal edge 11 and having the two free edges longitudinal edges 12 and 14 disposed adjacent to each other.

While in such folded condition as shown in Fig. 1, I provide a plurality of independent stitched loops 15 spaced from each other along the length of the folded fabric 10 and arranged in a predetermined position with respect to the longitudinal edge 11. Each stitched loop 15 is so arranged as to pierce the two layers 10a and 10b at two points 16 and 17 spaced from each other along the length of the folded fabric 10.

By reason of the above described arrangement of stitched loops 15, when the folded and stitched fabric is turned inside out and pressed, in the customary manner as practiced in the art, it will appear as shown in Figs. 4 and 5 where it is noted that sets of simulated bar tacks 21, 22 are spaced along the necktie to greatly enhance the appearance thereof. It is noted that although the stitched loops 15 are arranged in a lengthwise direction with respect to the necktie fabric in Fig. 1, when the said fabric is reversed the simulated bar tacks 21 and 22 will be disposed transversely of the length of the necktie. These visible stitched loop portions or tacks 21 and 22 are those components of the loops 15 which pierce the fabric layers 10a and 10b, at the points 16 and 17, while the loop portions 24 and 25 (see Fig. 3) overlying the fabric layers 10a and 10b respectively, are hidden from view.

In addition to having obtained the advantage of providing a handmade bar-tacked appearing necktie of distinctive design, I provide a construction in which the excessive distortion of the necktie, due to its longitudinal stretch while making up for wear, is prevented. Necktie fabrics are generally cut on the bias so as to render the finished necktie stretchable longitudinally. In the usual reversal method of stitching neckties, such as for example, that taught by the patent to Naftali, et al., No. 1,931,447, granted October 17, 1933, for Sewing machines, or my said Patent No. 2,174,993, the necktie is permitted to stretch

is overstretched to a point where the necktie, particularly along the edges is distorted by indented areas adjacent the stitching. In my improved method of construction as described in the present application, it is noted that the necktie will be permitted to stretch longitudinally only between the loop portion 21 of one pair of tacks and the loop portion 22 of the next succeeding pair of tacks. The material of the necktie between the tack portions 21 and 22 of each pair of tacks 21, 22 will resist stretching and thus while permitting resilient stretch of the necktie as a whole will at the same time prevent undue stretch and probable distortion.

In Figs. 7 and 8, I have shown a modified form of my invention in which the cut-to-pattern necktie fabric 33 is folded substantially longitudinally in half with the wrong side outermost to provide two layers 31 and 32 interconnected by a folded edge 33 and having free edges 34 and 35. However, in this form of my invention, before I stitch the layers 31 and 32 together with the independent loop stitches 36, similar in purpose and function to that of the loop stitches 15, I fold over, backwardly on itself, an edge portion of the layer 32 to provide a third layer 33 overlying the layer 32. It is noted that the loop stitches 36, in this form, pass through three thicknesses or layers of fabric material, which makes for a sturdier construction than that having two thicknesses or layers as described in the Figs. 1 to 6 form of my invention.

In the above described Figs. 7 and 8 form of my invention when the stitched fabric layers are turned inside out, the necktie will appear as shown in Figs. 4 and 5.

It will be seen from the above description and from the drawing that the stitched loops 15 or 36 are arranged in a longitudinal row and are variously spaced from the folded edge of the fabric in the positions shown in Figs. 1 and 7, with the result that when the necktie is turned inside out and a fold made along the row of said stitched loops 15 or 36, and pressed, the shape of the necktie is thereby determined.

While in the drawing I have illustrated my invention as applied to a type of four-in-hand necktie known in the trade as a self-lined necktie, it is understood that my inventive method may also be satisfactorily applied to other types of four-in-hand neckties, which may be folded differently and which may include a lining.

It will thus be seen that there is provided a method for manufacturing neckties by means of which the several objects of this invention are achieved, and which is well adapted to meet the conditions of practical use.

As various possible embodiments might be made of the above invention, and as various changes might be made in the matter hereinabove set forth, it is understood that all matter herein set forth or shown in the accompanying drawing is to be interpreted as illustrative and not in a limiting sense.

Having thus described my invention, I claim as new and desire to secure by Letters Patent:

15 1. In a method of making neckties, the steps comprising folding a necktie fabric longitudinally with the wrong side outermost to provide two adjacent layers interconnected by a first folded longitudinal edge, folding a portion of one of said two layers over on itself in a direction toward said first folded longitudinal edge to provide a third layer, stitching together the said three layers at a plurality of independent points spaced from each other along the length of said folded fabric, arranging said independent points of stitching in a line substantially parallel to the longitudinal axis of said folded fabric and spacing said line of independent points of stitching from said first folded edge a distance substantially equal to the width of the completed necktie, then turning said folded, stitched fabric inside out.

20 2. In a method of making neckties, the steps comprising folding a necktie fabric longitudinally with the wrong side outermost to provide two adjacent layers interconnected by a first folded longitudinal edge, folding a portion of one of said two layers over on itself in a direction toward said first folded longitudinal edge to provide a third layer, fastening together the said three adjacently disposed layers by a plurality of independent 25 stitched loops, spaced from each other along the length of the folded fabric, arranging each stitched loop in such manner that it will pierce the said three layers at two points spaced from each other along the length of said folded fabric, then turning said folded and stitched fabric inside out whereby the said piercing point portions of said stitched loops will be visible and appear as bar tacks, while the other portions of said 30 stitched loops will be hidden from view.

VALENTINE NAFTALL.
